CAN OPENING KEY

Henry William Abts III, New York, N.Y., assignor to
American Can Company, New York, N.Y., a corpora-
tion of New Jersey

Filed Dec. 4, 1961, Ser. No. 67,791

Term of patent 14 years

(Cl. D22—2)

Fig. 1.

Fig. 2.

FIGURE 1 is a front elevational view of a can opening key embodying my new design (a rear elevational view of the key would be substantially the same as shown in FIG. 1, except that the key would be in a reversed position and there would be no showing of the transverse indentation between the slot and the narrow end of the key); and

FIGURE 2 is a side elevational view of the same as viewed from the right of FIGURE 1 (an opposite side elevational view of the key would be substantially the same as shown in FIG. 2, except that the indentation would be in a reversed position, and an edge of the free end of the handle would be visible).

The design of the key is characterized by the formation of its handle which is bilaterally asymmetrical and is disposed on a center line which obliquely intersects the center line of the key shank.

I claim:

The ornamental design for a can opening key, as shown and described.
